(57) **CLAIM**

The ornamental design for a component for aiding connection of a dry cell battery to a portable device, as shown and described.

DESCRIPTION

FIG. 1 is a front view of a component for aiding connection of a dry cell battery to a portable device showing my new design in a position of use. The broken line of the connector shown in FIG. 1 is for illustrative purposes only and forms no part of the claimed design. The broken lines which define the bounds of the claimed design form no part thereof;

FIG. 2 is a rear view thereof;

FIG. 3 is a left side view thereof;

FIG. 4 is a right side view thereof;

FIG. 5 is a top plan view thereof;

FIG. 6 is a bottom plan view thereof;

FIG. 7 is a perspective view thereof from the rear side; and,

FIG. 8 is a perspective view thereof from the front side.
